CLAIM

The ornamental design for a baseplate for EEG logger, as shown and described.

DESCRIPTION

FIG. 1 is a top view of a first embodiment of a baseplate for EEG logger according to the new design;

FIG. 2 is a front view of the baseplate for EEG logger of FIG. 1;

FIG. 3 is a side view of the baseplate for EEG logger of FIG. 1;

FIG. 4 is a rear view of the baseplate or EEG logger of FIG. 1;

FIG. 5 is a top perspective view of a second embodiment of the baseplate for EEG logger according to the new design; FIG. 6 is a top perspective view of the baseplate for EEG logger of FIG. 1, showing the EEG logger inserted; and, FIG. 7 is a bottom view of the baseplate for EEG logger of FIG. 1;

The broken lines in FIGS. 1–5 and 7 depict portions of the baseplate for EEG Logger that form no part of the claimed design. The additional broken lines in FIG. 6 depict environmental subject matter and form no part of the claimed design.

The dotted lines shown in the drawings depict boundaries of the claimed design and form no part thereof.
